UNITED STATES PATENT OFFICE.

HENRY C. DUNN, OF ERIE, PENNSYLVANIA.

BRICK-KILN.

SPECIFICATION forming part of Letters Patent No. 664,136, dated December 18, 1900.

Application filed August 11, 1900. Serial No. 26,585. (No model.)

To all whom it may concern:

Be it known that I, HENRY C. DUNN, a citizen of the United States, residing at Erie, in the county of Erie and State of Pennsylvania, have invented certain new and useful Improvements in Brick-Kilns; and I do hereby declare the following to be a full, clear, and exact description of the invention, such as will enable others skilled in the art to which it appertains to make and use the same, reference being had to the accompanying drawings, and to the letters of reference marked thereon, forming part of this specification.

My invention relates to improvements in brick-kilns, and particularly to that type thereof which embodies substantially a series of adjacent independent chambers capable of being operated serially, so that while brick are being burned in some of the chambers other chambers are being cooled and the burned brick removed therefrom and still other chambers are being filled with brick preparatory to their being burned.

The invention consists, substantially, in the arrangement of the chambers and the chimney relatively thereto and in the construction and arrangement of draft-flues leading from the ends of said chambers into the chimney, together with other details of the construction and of the arrangement of the parts thereof, whereby the different chambers of the kiln can be successively filled and operated without in any wise interfering with or impeding the operation or non-operation of other chambers of the kiln. In other words, the parts of the kiln are so constructed and arranged that it operates as a continuous kiln, all of which features are hereinafter fully set forth in the accompanying drawings, in which—

Figure 1 is an end view in elevation of my improved brick-kiln. Fig. 2 is a side view of the kiln, partially in elevation and partially in section, on the line *u u* in Fig. 1 looking in the direction of the arrow. Fig. 3 is a vertical longitudinal section of the kiln on the line *v v* in Figs. 1, 4, 6, and 7 looking in the direction of the arrows. Fig. 4 is a transverse vertical section of the kiln on the lines *w w* in Figs. 3, 5, 6, and 7 looking in the direction of the arrows. Fig. 5 is a vertical longitudinal section of the kiln on the lines *x x* in Figs. 1, 4, 6, and 7 looking in the direction of the arrows. Fig. 6 is a horizontal section of the kiln on the lines *y y* in Figs. 1, 2, and 3 looking in the direction of the arrows. Fig. 7 is a top or plan view of the kiln, with portions broken away, showing the arrangement of the draft-flues. Fig. 8 is a view of a portion of the kiln, partially in vertical section, on the line *z z* in Figs. 6 and 7 looking in the direction of the arrow.

In the drawings thus illustrating my invention the end walls *A* of the kiln are made without openings except the ends of the longitudinal draft-flues *B B* and *B'*, (see Fig. 1,) which are normally closed by some convenient closures *b* and only opened when it is necessary to clean the flues *B B* and *B'*. The side walls *D* of the kiln are provided with an arched opening *C*, (see Fig. 2,) communicating with each chamber *E* of the kiln. After a chamber is filled the opening *C* is closed up during the burning of the brick by walling it up with brick and plastering it over with mud or in any other convenient manner. The ends of the transverse draft-flues *F* and *F'* also open through the side walls *D* of the kiln, but are normally closed by some convenient closure *f* and are only opened when it is necessary to clean the flues *F* and *F'*.

The kiln shown in the drawings consists of a series of twenty-two independent adjacent chambers *E*, separated from each other by a longitudinal vertical wall *E'* and by transverse walls *E²* and are numbered from "1" to "22," inclusive, each of which is provided with one of the openings *C*, hereinbefore described, and with vertical flues *e* at the outer ends thereof communicating with the side draft-flues *B* and like flues *e'* at the inner ends thereof communicating with the central draft-flue *B'*, the side draft-flues *B* being connected with the central draft-flues *B'* by means of transverse draft-flues *F* and *F'*, as clearly shown in Fig. 7. Through the bottom of each of the transverse walls *E²* there is a series of draft-openings *e²*, so that there is communication between the chambers *E* therethrough to supply air to said chambers, and through the bottom of each end of the longitudinal wall *E'* there is a draft-opening *e³*, through which communication is had between

the chambers E Nos. 1 and 22 and between chambers E Nos. 11 and 12, so that air may be supplied therethrough.

In the center of the kiln there is a chimney G, into which the draft-flues B B', &c., discharge, as shown in Fig. 7. These flues B B', &c., are controlled by cut-off dampers H, (see Figs. 2, 3, and 7,) whereby parts of the said flues may be cut off from communication with the chimney G when desired. The tops of the vertical flues e e', opening into the horizontal draft-flues B B and B', are provided with shut-off dampers I, provided with handles I', as illustrated in Figs. 2, 3, and 8, whereby any of the chambers E may be cut off from communication with the draft-flues B B', as desired. In the top of each of the chambers E there is a series of openings J (shown only in two chambers, see Figs. 7 and 8) for introducing fuel into the chambers E, which openings are provided with covers J', as clearly shown in the sectional view of one of the chambers E in Fig. 8. Along the center of the top of each chamber E there are also holes K, provided with covers k, for inspecting the brick while being burned and determining when the burning is completed. (See Figs. 7 and 8.)

In operation the brick to be burned are placed in one or more of the chambers E—for example, Nos. 1, 2, &c.—and the front openings C thereto closed. They are then fired and fuel supplied from time to time thereto through the openings J in the top of each chamber, air being supplied to support combustion through the openings e² in the transverse division-walls E², while the products of combustion pass through the flues e e' and the draft-flues B B', &c., to the chimney G. Meanwhile other adjacent chambers E—for example, Nos. 4, 5, &c.—are filled with brick and in a like manner fired, and as the first-named chambers have by this time been sufficiently burned they are shut off and are allowed to cool, while at the same time other chambers E are being filled with brick and fired. This operation is continued, so that after the kiln is in full operation by utilizing the system of flues and dampers heretofore described I am enabled to utilize the heat from chambers being cooled to start the burning of the chambers newly filled, and in this manner can utilize the heat so as to greatly economize in the use of fuel and keep a portion of the chambers constantly in operation while the other portions are being cooled and the burned brick removed and the chambers refilled, so that the kiln is continuously operating.

Having thus described my invention, so as to enable others to construct and operate the same, what I claim as new, and desire to secure by Letters Patent of the United States, is—

1. The combination in a brick-kiln of permanent side and central longitudinal walls, a series of permanent transverse walls extending from the side walls to the central wall forming the ends of the kiln and also dividing it into a series of chambers, arched chamber-roofs extending between said side and central walls, draft-flues through said transverse walls from one chamber to another, a chimney located centrally in said kiln, a longitudinal horizontal flue in the upper part of the central longitudinal wall, communicating with the chimney and with the inner end of each chamber by means of vertical flues in the central wall, a longitudinal horizontal flue in the upper part of each of the side walls of the kiln, communicating with the outer ends of said chambers by means of vertical flues in the side walls, transverse horizontal flues connecting the side flues with the central flue, dampers for cutting off the vertical flues from the horizontal flues, and dampers for cutting off portions of the central and side flues, substantially as and for the purpose set forth.

2. In a brick-kiln the combination of permanent side and end walls, a central longitudinal wall, and permanent transverse walls therefrom to the side walls so as to form two rows of adjacent chambers having their rear ends separated by said central longitudinal wall, a series of draft-passages through the lower portions of each of said transverse walls, and a draft-passage through said longitudinal wall near each end thereof, a chimney located centrally in the said kiln, a longitudinal flue in the upper portion of each of the side walls of the kiln, a longitudinal flue in the upper portion of the central longitudinal wall and extending into the chimney, a transverse flue at each side of the chimney connecting the side flues with the central flue, vertical flues connecting the ends of said chambers with said central and side flues, dampers for shutting off the vertical flues, and dampers for cutting off portions of said horizontal flues, substantially as and for the purpose set forth.

In testimony whereof I affix my signature in presence of two witnesses.

HENRY C. DUNN.
